UNDERFEED STOKER

Herbert E. Preston, Philadelphia, Pa., assignor to
American Engineering Company, Philadelphia,
Pa., a corporation of Pennsylvania

Application October 3, 1933, Serial No. 691,932

6 Claims. (Cl. 110—44)

This invention relates to furnace stokers, and more particularly to stokers of the multiple retort underfeed type.

One object of the present invention is to provide adjustable means adjacent to the main fuel feeding mechanism of a stoker whereby the depth of the fuel bed and the density of the fuel may be varied to best suit the operation conditions of the furnace.

10 A more specific object is to provide in a stoker of the stated character, a ram box extension plate which is adapted to be moved to and held in different positions of adjustment, whereby the density and depth of the fuel bed may be varied 15 and thus insure the best efficiencies under all conditions of operation.

20 A further object is to provide a ram box cap extension plate which is simple in construction, and which may be readily renewed without disturbing other elements of the stoker.

Other and further objects will become apparent as the description of the invention progresses.

Of the drawings:

Fig. 1 is a fragmentary side view taken through 25 one of the retorts of an underfeed stoker showing one of the adjustable ram box extension plates.

Fig. 2 is a view taken substantially along line 2—2 of Fig. 1.

Fig. 3 is a sectional view taken substantially 30 along line 3—3 of Fig. 1, and

Fig. 4 is a plan view of one of the adjustable ram box extension plates.

Referring to the drawings, the numeral 1 designates generally a conventional stoker of the multiple retort underfeed type comprising alternately disposed retorts 2, and tuyère rows 3. The side walls 4 of the retorts 2 are secured at the upper ends thereof to brackets 5 provided in a front wall 6. Fuel from a hopper 7 is fed to the retorts 2 by a series of reciprocating rams 8 operating in cylinders 9 secured to the front wall 6.

The brackets 5 are substantially rectangular in cross section, as shown in Fig. 3, and are in substantial alignment with the tuyère rows 3.

45 Bridging the space between adjacent brackets 5 are a series of air boxes 10 and 11. Air box 10 is provided with flanged depending legs 12 and 13 which are bolted respectively to the upper surfaces of the associated brackets 5. Air box 50 11 is likewise provided with flanged legs 14 and 15 which are also bolted respectively, to the upper surfaces of brackets 5, and air boxes 10 and 11, are substantially flat, as shown in Figs. 1 and 55 3, and form supports for the masonry 16. Air

boxes 10 and 11 are substantially triangular in cross section, as shown in Fig. 1, and the bottom walls 17 and 18 respectively thereof are in substantial alignment and incline upwardly from front to rear of the wall 6. The bottom wall 18 of air box 11 terminates at the forward end thereof in a depending portion 19 having a slightly inclined surface 20 which extends to the mouth of cylinder 9. Depending portion 19 is provided with an open cylindrical recess 21 which receives the correspondingly-shaped forward end portion 22 of a ram box extension plate 23. End portion 22 is provided with a radial slot 24 which engages a rod 25 extending longitudinally of recess 21, and which is suitably secured at the ends thereof to the legs 14 and 15 of air box 11. Plate 23 is substantially rectangular in shape (Fig. 4), it occupying substantially the entire space between adjacent brackets 5, and the free end 40 thereof extending substantially to the inner surface of wall 20 10. Plate 23 is secured in adjusted position by bolts 26 and 27, which extend through internally threaded openings provided in ears 28 and 29 extending from the upper surface of plate 23 near the free end thereof. To adjust plate 23 to any of 15 its positions of adjustment it is only necessary to loosen the bolts 26 and 27 and swing the same about rod 25 to the new position and then tighten bolts 26 and 27. The ends of bolts 26 and 27 frictionally engage the inner surfaces of legs 12 and 13 of air box 10, or the side walls of brackets 5 20 depending upon the position to which the plate is adjusted. Apertures may be provided in the side walls of brackets 5 and in legs 12, and 15 for receiving these bolts if a more positive securing 25 means is desired. In the present instance a pair of blocks 30 and 31 are provided between plate 23 and air box 10 to further secure the plate against upward movement during operation of 30 the stoker. A series of reinforcing ribs 32 are also 35 provided on the upper surface of plate 23 as shown in Fig. 4, the lower surface of plate 23 being smooth and in substantial alignment with the inclined surface 20 of depending portion 19, thereby presenting a smooth continuous surface 40 to the fuel fed by the rams 8.

An upper coal plate 33 extends from the mouth of cylinder 9 and rests upon a dead plate 34 provided in the bottom of the retort 2, forming the bottom wall of the opening in wall 6 through 45 which the fuel fed by ram 8 passes to the retort 2.

It therefore is seen that when it is desired to increase the depth of the fuel bed it is only necessary to swing plate 23 upwardly the desired 50

amount and secure the same in position. On the other hand, if it is desired to decrease the depth of the fuel bed, or to pack the fuel more tightly, plate 23 is lowered. By this construction it is possible to regulate the fuel bed so as to obtain the best efficiencies in operation, and also to enable the furnace to efficiently burn different kinds of fuel.

While the device herein described is admirably adapted to fulfill the objects primarily stated, it is to be understood that it is not intended to confine the invention to the one embodiment herein shown since it may be embodied in other forms, all coming within the scope of the claims which follow.

What is claimed is:

1. In an underfeed stoker, the combination of a retort, a fuel feeding ram for said retort, of a wall disposed between said ram and said retort having a passage therein through which the fuel fed by said ram passes to said retort, an adjustable ram box extension plate comprising a portion of the upper wall of said passage for regulating the depth and density of the fuel in said retort, means for pivotally supporting one end of said plate and means provided near the other end of said plate for retaining the same in different positions of adjustment.

2. In an underfeed stoker, the combination of alternately disposed retorts and tuyère rows, of a fuel feeding ram for each retort, a wall disposed between said retorts and rams having passages therein through which the fuel fed by said rams passes to said retorts, an adjustable ram box extension plate for each passage, said plates forming a portion of the upper walls of said passages, means for pivotally supporting one end of said plates and means provided near the other end of said plates for retaining the same in different positions of adjustment.

3. In an underfeed stoker, the combination of a retort, a fuel feeding ram for said retort, of a wall disposed between said ram and said retort having an opening through which the fuel fed

by said ram passes to said retort, adjustable means provided in the upper wall of said passage for varying the depth and density of the fuel in said retort, said means comprising a plate, a cylindrical recess for receiving one end of said plate, interlocking means provided on said plate and in said recess to prevent longitudinal movement of said plate, and means provided in the other end of said plate for retaining the same in various positions of adjustment.

4. In an underfeed stoker, the combination of a retort, a fuel feeding ram for said retort, of a wall disposed between said ram and retort, having an opening therein through which the fuel from said ram passes to said retort, an adjustable ram box extension plate comprising the upper wall of said passage, a cylindrical recess for receiving one end of said plate, a rod extending through said recess, a slot provided in said plate adapted to engage said rod and adapted upon a predetermined movement of said plate to hold the latter against longitudinal movement while permitting said plate to swing about said rod as a pivot, and means for securing the plate in various positions of adjustment.

5. A ram box extension plate, comprising a substantially rectangular body portion, substantially cylindrical means provided at one end of said plate, means provided in said cylindrical means adapting said plate for pivotal movement, and locking means provided on said plate for holding the same in adjusted position.

6. An adjustable ram box extension plate, comprising a substantially rectangular body portion, substantially cylindrical means provided at one end of said plate, a slot provided in said cylindrical means adapted to receive interlocking means for pivotally mounting said plate, projections provided on the side edges of said plate adapted to receive locking bolts to retain said plate in adjusted position, and reinforcing ribs provided on said plate.

HERBERT E. PRESTON.
